UNITED STATES PATENT OFFICE.

WILLIAM GEORGE BEATTY, OF FERGUS, ONTARIO, CANADA.

WRINGER.

Application filed January 4, 1922. Serial No. 527,026.

To all whom it may concern:

Be it known that I, WILLIAM GEORGE BEATTY, of the town of Fergus, in the county of Wellington and Province of Ontario, 5 Dominion of Canada, have invented certain new and useful Improvements in Wringers; and I hereby declare that the following is a full, clear, and exact description of the same.

10 This invention relates to a wringer provided, below the rollers, with substantially horizontal slideways supporting a horizontally adjustable drain board which can be selectively positioned, either to carry away 15 the water wrung from the articles, or, to allow the water to fall back into the tub with which the wringer is used.

The invention further relates to adjusting means for the drain board, comprising a 20 rock shaft and a connection between the rock shaft and the drain board which will selectively position it with relation to the rollers.

The invention further relates to a tray 25 for a wringer in which the pan is of a substantially rectangular shape and comprises a bottom having upturned flanges along two opposite sides and down turned flanges along the other two sides, the bottom and 30 upturned flanges providing a channel or fixed path along which the articles pass from the rollers, the downturned flanges being of such shape and depth as to protect the articles against injury during their delivery from the rollers to the tray and from 35 the tray to the clothes basket or other receptacle placed to receive them; the tray being supported at one end by the structure of the wringer and at the other end by a swing- 40 ing bail having a connection with the upturned flanges, the dimensions of the bail being suitably proportioned to the apparatus with which the tray is used.

In the drawings:

45 Fig. 1 is a sectional elevation of a wringer showing the drain board and tray with the drain board positioned to carry the water away from the rollers.

Fig. 2 is a similar view to Fig. 1, showing 50 the drain board positioned to allow the water to fall back into the tub.

Fig. 3 is an inverted plan view on a smaller

scale than Figs. 1 and 2, showing the rock shaft and the connection between the rock shaft and the drain board.

Fig. 4 is a fragmentary detail view of the 55 rock shaft in the position shown in Fig. 2, and

Fig. 5 is a sectional elevational view of the 60 wringer and a fragment of the washing machine showing the use of the tray.

Those parts of the wringer, except as hereinafter described, may be of any usual or approved construction, as the drain board is capable of use, not only with the specific 65 type of wringer shown in the drawings, but is also capable of use in connection with any other type of manual or power driven wringing apparatus, and therefore only such parts of the wringer will be referred to as may be 70 necessary to describe the use and general principle of the construction of the present invention.

Journalled in the wringer frame 1, are 75 the usual rollers 2 and 3 below which the inner surfaces of the frame 1 are provided with horizontal, or substantially horizontal, slideways 4 to movably support the drain board.

The drain board comprises a bottom 5 which is seated on the lower members of the slideways 4, to move laterally with relation to the rollers, and the front edge 6 of the bottom 5 is curved downwardly to form a spill-way for the liquid falling on 80 the drain board and direct it into the receptacle placed to receive it, and also to provide a curved surface for the articles passing over the drain board and protect them from injury or abrasion when in contact 85 with the bottom 5.

At the inner end of the bottom 5 is an upturned flange 7 and along the sides of the bottom 5 are upturned flanges 8 to form a pan for the water from the rollers. At 90 the inner end of each slideway 4 is a stop 9 against which abuts the flange 7 when the drain board is moved to the limit of its inward position. Journalled in the frame 1, below the slideways 4 is a cranked rock shaft 10, and on the outer end of the rock shaft is a handle 11 by which it is actuated.

Extending downwardly from the under surface of the bottom 5 are two sets of

spaced lugs 12 and contained between them is the transverse member 13 of the pitman. The pitman consists of two arms 14 and the transverse member 13 the arms 14 being 5 formed with eyes 15 which embrace the cranked rock shaft 10. Passing through the lugs 12 below the connecting member 13 are split pins 17, which prevent the transverse member 13 becoming displaced from 10 between the lugs 12.

When the handle 11 is turned into the position shown in Fig. 1, it rocks the crank shaft 10 to draw the pitman in the direction of the roller 3, this action of the shaft and 15 pitman moving the drain board into position below the rollers, so that the water from the articles passing through the wringer will fall upon the drain board.

By turning the handle 11 into the position shown in Fig. 2, the shaft 10 and pitman move the drain board outwardly from the rollers, the water from the rollers then falls back into the tub or other apparatus with which the wringer is used.

25 The wringer is provided with a splash board 19 hinged to the frame 1, below the rock shaft 10, which is so located as to form a stop for the turning movement of the rock shaft and the sliding movement of the drain board in an outward direction, the movement of these parts in an inward direction being arrested by the stop 9.

The tray comprises a bottom 21 of substantially rectangular shape having upturned flanges 22 along two opposite sides and downturned flanges 23 and 24 along the other two sides. The wringer ends of the flanges 22 are chamfered as shown at 27, to clear the bearings 25 for the idler 26.

40 The frame 1 is provided with notched lugs 30 to overlie the top edges of the upturned flanges 22 and engage their inner surfaces, when the tray is assembled with the drain board.

45 At the delivery end of the tray is a bail comprising two arms 32 and a connecting piece 33, the bail being hingedly secured to the pan by rivets 34 passing through the arms 32 and through the upturned flanges.

50 When the tray is assembled with the wringer, the bail is turned into a position in which the connecting piece rests upon the lid 35 of the wash tub 36 and the arms 32 are in a more or less vertical position thereto.

55 As shown in the drawings, the notched lugs 30 are above and spaced from the stops 9, and during the assembly of the tray with the wringer, the bottom of the pan is passed across the top of the stops 9 until its progress is arrested by the chamfered edges 27 of the upturned flanges coming into contact with the bearings 25, the notches of the lugs 30 providing for the passage of the upturned flanges through them, this arrangement of the notched lugs 30, stops 9 and

bearings 25 securely holding the wringer end of the pan in its set position when assembled with the wringer.

The downturned flange 23 at the wringer end of the bottom is preferably of a depth 70 to overlap the flange 7 of the drain board and by its engagement with the flange 7 securely lock the tray in its assembled relation with the drain board and the parts of the wringer. The flange 24 at the delivery 75 end of the tray is preferably curled under the pan to provide a roll edge which will not injure the fabrics, as they pass from it.

In assembling the tray with the drain board, the latter is moved in the direction of 80 the rollers until its motion is arrested by the stops 9. The wringer end of the tray is then entered in the slideways formed by the stops 9 and the lugs 30, until the flanges 22 85 abut against the bearings 25 and the flange 23 is interlocked with the flange 7, the interlocking of the flanges 7 and 23 preventing the inadvertent displacement of the tray during the use of the apparatus.

Having thus fully described my invention, what I claim as new and desire to secure by Letters Patent is:

1. A wringer, comprising a set of rollers, a laterally adjustable drain board slidably mounted below the rollers, and means adjusting the drain board relatively to the rollers, comprising a rock shaft and a pitman communicating motion from the rock shaft to the drain board.

2. A wringer, comprising a set of rollers, a laterally adjustable drain board slidably mounted below the rollers, and means adjusting the drain board laterally to the rollers, comprising a rock shaft, a pitman communicating motion from the rock shaft to the drain board, and means for arresting the movement of the rock shaft and the drain board at the limit of motion in both directions.

3. In a wringer comprising a set of rollers and a drain board below the rollers, the combination of a removable tray, supports forming part of the wringer for one end of the tray, and a bail pivotally connected to the tray supporting the other end, said tray having a downturned flange overlapping and interlocking with the adjacent end of the drain board.

4. In a wringer the combination of a pair of rollers, a drain board beneath said rollers, having an upturned flange, a removable tray having a downturned flange overlapping and interlocking with the flange of the drain board, and supports removably maintaining the tray in its set position with relation to the drain board.

5. In a wringer the combination of a pair of rollers, a reciprocatingly movable drain board, below the rollers, having an upturned flange, a removable tray having a down-

turned flange overlapping and interlocking with the flange of the drain board and supports for removably maintaining the tray in its set position with relation to the drain board.

6. In a wringer the combination of a pair of rollers, a drain board below the rollers, having an upturned flange, a removable tray having a downturned flange overlapping and interlocking with the flange of the drain

board, supports forming part of the wringer, and other supports connected to the tray for maintaining it in its set position with relation to the drain board.

Dated at the said town of Fergus, this 20th 15
day of December, A. D. 1921.

WILLIAM GEORGE BEATTY.
